DESIGN FOR A SLIPPER OR SIMILAR ARTICLE

Thomas R. Ingram, Glen Ellyn, Ill., assignor to Groves & Ingram, Chicago, Ill., a partnership

Application December 1, 1944, Serial No. 116,659

Term of patent 14 years

(Cl. D7—7)

To all whom it may concern:

Be it known that I, Thomas R. Ingram, a citizen of the United States, residing in the village of Glen Ellyn and State of Illinois, have invented a certain new, original, and ornamental Design for a Slipper or Similar Article, of which the following is a specification, reference being had to the accompanying drawing, forming a part thereof.

Fig. 1 is a side elevational view of a slipper, showing my new design.

Fig. 2 is a plan view.

Fig. 3 is a front perspective view.

I claim:

The ornamental design for a slipper or similar article, substantially as shown.

THOMAS R. INGRAM.
